APPARATUS FOR HIGH-FREQUENCY
INDUCTION HEATINGHerbert F. Storm, West Allis, Wis., assignor to
Sunbeam Corporation, a corporation of Illinois

Application June 7, 1944, Serial No. 539,108

1 Claim. (Cl. 219-13)

1

This invention relates to an apparatus for high-frequency induction heating and more particularly to an apparatus of such type for heating work pieces having sharply convex surface portions, such as edges, ribs, corners or lugs, and concentrating the heating effect at such convex surfaces.

It often occurs that some salient portion of the surface of a mechanism is subject in operation to intense localized wear. It is desirable to be able to heat and temper the surface of the mechanism in this region but it is often undesirable to extend the heating and tempering to other portions of the mechanism, which would tend to impair the elasticity and toughness of the structure as a whole. In other words, it is desirable to be able to concentrate the heating and tempering to the portion of the surface of the mechanism subjected to the wear and it has been found that a high-frequency induction heating system is particularly suitable for this purpose inasmuch as the heating effect of a high-frequency induction field varies from point to point with the intensity of the field. By a proper design of the heating inductor its field can be given the desired intensity distribution characteristic.

While the invention is of general application, it is illustrated as applied to the local heating and tempering of the shoulder of a gun breech, which shoulder engages the rim of the shell casing. By local heating and tempering of the gun breech shoulders, it has been found that the number of firings of a gun embodying the breech, without repair or replacement, may be increased many times.

It is an object of the invention to provide new and improved high-frequency induction heating apparatus for treating a work piece having a sharply convex surface portion and concentrating the heating effect at such convex surface portion.

In accordance with the invention, a high-frequency induction heating apparatus for heating a work piece having a sharply convex surface portion and for concentrating the heating over a predetermined portion of the convex surface of the work piece comprises a support, a heating inductor mounted on the support and proportioned to develop a high-frequency magnetic field including, in the absence of a work piece, a portion of maximum intensity which is of the same order of magnitude over its cross-sectional area. The apparatus also includes positioning means mounted on the support for locating the

2

work piece within the field with the predetermined convex surface portion thereof effectively cutting across the maximum intensity portion of the field.

5 The invention, both as to its organization and method of operation, together with further objects and advantages thereof, will best be understood by reference to the specification taken in connection with the accompanying drawings, in 10 which:

Fig. 1 is a perspective view of a gun breech to the heat treatment of which the application of the invention is illustrated;

Fig. 2 is a graph of the magnetic field of a 15 single turn heating inductor to aid in the explanation of the invention;

Figs. 3 and 4 are graphs of the magnetic fields of an alternative form of heating inductor to aid in explaining the invention;

20 Figs. 5 and 6 are an end view and a front elevation, respectively, of a high-frequency induction heating apparatus embodying the invention;

Figs. 7 and 8 are detailed views of an alternative form of heating inductor suitable for use 25 in the apparatus of Figs. 5 and 6; and

Figs. 9 and 10 are schematic representations 30 of alternative forms of heating inductors effective to concentrate the heating effect more sharply at a single point or region on the surface of the work piece.

Referring now to Fig. 1 of the drawings, there is illustrated as a work piece for heat treatment by the high-frequency induction heating apparatus of the invention a gun breech 10 which is essentially an elongated bifurcated element having a pair of arms 10a, 10b joined by end bridging members 10c and 10d. Each of the arms 10a, 10b has an elongated sharp edge 10e which terminates in a shoulder 10f, the edges 10e and shoulders 10f comprising sharply convex surface portions of the arms. The cross sections of the arms 10a and 10b throughout the portions thereof which are intersected by the sharp edge 45 portions 10e are elongated and the sharply convex surface portions 10f include one end of the cross sections of the arms 10a, 10b at such points. In the breech described the regions 10g of the arms 10a, 10b, including the surface portions 50 10f, indicated in dotted lines, are subject to extreme wear in use. Therefore it is desired to heat treat these localized portions of the gun breech to harden them and reduce wear without substantially heat treating the remaining portions of the gun breech, which might tend to

impair the toughness and elasticity of the breech as a whole.

In Fig. 2 is represented schematically a single-turn heating inductor 11 in close association with an arm 10b of the work piece of Fig. 1, the arm 10b being shown schematically for simplicity and having a cross-sectional configuration similar to the cross section 10h taken through the shoulder 10f. Such a relationship with respect to the arm 10b is similar to that which would be obtained if the heating inductor 11 were disposed in the slot of the element 10 with the center of inductor approximately at the shoulder 10f. The field of inductor 11 in the absence of the work piece 10b is shown in the full lines, this being conventional representation of a field of a single turn coil, the field being substantially toroidal and having a portion of maximum and approximately uniform intensity within the coil. It is understood that the intensity of the field at any point is inversely proportional to the distance between adjacent field lines. Giving effect now to the presence of the work piece 10b, it is seen that the latter crowds the field primarily in the region of the surface 10i and, since the heating effect varies directly with the intensity of the high-frequency field over the extent of the work piece, it is clear that the maximum heating effect on the work piece 10b is in the region around point 10i. On the other hand, the intensity of the magnetic field, and therefore the heating effect, at the point 10f is relatively low. Therefore such an arrangement is not suitable for concentrating the heat treatment in the regions 10g of the work piece 10.

Now referring to Figs. 3 and 4, the single-turn inductor 11 is replaced by a pair of spaced inductors 12 and 13 excited in such a way that their fields are in aiding phase. As indicated in Fig. 3, under such circumstances the field between the inductors 12 and 13 is an elongated approximately uniform field of maximum intensity which approximates that of a continuous solenoid having a length equal to the spacing of the inductors 12 and 13, such a solenoid enclosing a field of substantially uniform and maximum intensity. If now the work piece 10b is inserted between the coils as indicated in Fig. 4, effectively cutting across the maximum intensity portion of the field between the inductors 12 and 13, the high-frequency field cannot substantially penetrate the work piece 10b, due to the skin effect, but is pushed up or crowded around it, intensely concentrating the field at the point 10f and developing a field of somewhat lesser but high intensity at the point 10j. With such an arrangement, then, the heating effect of the inductors 12 and 13 is very highly concentrated at the sharply convex surface portion 10f and concentrated to a lesser degree at the sharply convex surface portion 10j, while all other surface portions of the arm 10b are heated to a correspondingly lesser degree.

Referring now to Figs. 5 and 6, there is illustrated schematically a high-frequency heat-treating apparatus embodying the principal of concentration of the heat treatment represented in Fig. 4, by means of which the heating may be concentrated over a predetermined portion of one or more sharply convex surface portions of a work piece, in the example illustrated the concentration being at a single sharply-convex surface portion of each arm of the gun breech 10. The apparatus of Figs. 5 and 6 comprises a

base or support 14 having back vertical support or flange 14a and a heating inductor 15 mounted on the support by means of rigid projecting leads or conductors 15e extending through the support 14a. The inductor 15 is proportioned to develop an elongated high-frequency magnetic field including, in the absence of a work piece, a portion of maximum intensity which is of the same order of magnitude over its cross-sectional area. To this end the inductor 15 includes two pairs of coaxial coils 15a, 15b and 15c, 15d the coils of each pair being spaced and being wound and connected so that their magnetic fields are in aiding phase, while the pairs of coils are preferably wound and connected so that their fields are in opposing phase. By this arrangement an elongated field of approximately uniform intensity is developed between the coils of each pair and extending over the area of the coils.

The apparatus of Figs. 5 and 6 also includes a positioning means for the work piece 10 which, for the sake of clarity, is represented in dotted lines. This positioning means may be a stud 16 mounted on the support 14 and having a beveled end portion 16a to facilitate sliding the work piece 10 over the stud 16. The positioning means 16 is effective to locate the work piece 10 with each of its arms extended between the coils of one of the pair of coils and with the sharply convex surface portions or shoulders 10f thereof effectively cutting across the maximum intensity portions of the fields of the pairs of coils 15a, 15b and 15c, 15d. Specifically the location of the work piece 10 with respect to the heating inductors 15 is as represented in the cross-sectional view of Fig. 4, that is with the end of the cross section of the arms 10a, 10b included in the sharply convex surface portions or shoulders 10f approximately at the centers of the maximum intensity portions of the fields between the coils of each of the pairs 15a, 15b and 15c, 15d. Further, as shown in Fig. 4 and in Fig. 5, the other end of the cross sections of the arms 10a, 10b extend outside of the inductor coils and into a portion of the field of substantially lesser intensity.

The coils of the heating inductor 15 and its leads 15e are preferably formed from hollow copper tubing and are connected through insulation joints 17 to a cooling fluid circulating pump 18. The leads 15e are also connected to a source of high-frequency oscillations 19, connected to be energized from a power supply circuit 20 through a switch or circuit breaker 21. Preferably, the high-frequency source 19 is of the improved form disclosed and claimed in copending application Serial No. 539,106, Herbert F. Storm, filed June 7, 1944, and assigned to the same assignee as the present invention.

The heating apparatus also preferably includes adjustable quenching means mounted on the support 14 for quenching the work piece after heating. This means may comprise a pair of nozzles 22 mounted in a cross piece 23 pivotally supported at each end from arms 24 connected to a pair of vertical standards 25 mounted on the support or base 14. The pivotal axis of the cross piece 23 supporting the nozzles 22 is parallel to the longitudinal axis of the inductor 15 and permits pivotal adjustment of the nozzles for quenching a predetermined surface portion of the work piece 10 after heating. The nozzles 22 are connected through quenching fluid pipes 26 and a

valve 27 to a source of supply of quenching fluid, such as pipe 28.

In operation, the heating inductor 15 is excited from the high-frequency source 19 upon connecting it through the switch 21 to the power supply circuit 20. Simultaneously, the cooling fluid pump is put into operation to circulate cooling fluid through the hollow conductor of the inductor 15 thereby to prevent excessive heating thereof by its own high-frequency magnetic field.

Thus it will be seen that the apparatus of Figs. 5 and 6 described above comprises a high-frequency induction heating system for heating an elongated work piece 10 each of the arms of which has an elongated cross section and two sharply convex surface portions 10f including one end of the cross section, that is two sharp edge portions 10e which intersect one end of the cross section 10h. In the operation of this system the heating is substantially concentrated over a predetermined portion of the two convex surface portions or edges in the regions 10g. This concentration of the heating is effected by developing an elongated high-frequency magnetic field between the coils of each of the pairs of coils 15a, 15b and 15c, 15d of the heating inductor which, in the absence of the work piece, constitutes the portion of the total field of the inductor coils of maximum intensity, which intensity is of the same order of magnitude over its cross-sectional area, that is over the area of the coils. The work piece is then positioned by means of the stud 16 so that the arms 10a, 10b thereof are within and extended across the fields of the pairs of inductor coils 15a, 15b and 15c, 15d, respectively, with the sharply convex surface portions or edges 10f thereof effectively cutting across this maximum intensity portion of the field and crowding the field, as represented in Fig. 4. The cross section of each of the arms 10a, 10b included in these sharply convex surface portions is located approximately at the center of such maximum intensity portion of the magnetic field and effectively cutting across it. By this arrangement, as explained above, the heating is substantially concentrated at the surface portions 10f while the other end of the cross sectional area of each of the arms 10a, 10b extends outside of the maximum intensity portion of the field of its associated coil and into a portion of the field of substantially lesser intensity so that it is heated to a relatively lesser extent.

After the concentrated heating of the surface portions 10f of the work piece 10 as described, quenching fluid is supplied to the nozzles 22 from the supply pipe 28 by means of the valve 27, while these nozzles may be pivotally adjusted to confine the quenching action primarily to the surface portions of the work piece 10 on which the heating has been concentrated. By the system described, therefore, the heat treating of a work piece may be substantially concentrated on predetermined sharply convex surface portions while minimizing the heat treatment of other portions of the work piece, thereby minimizing any effect on the structural toughness and elasticity of the work piece as a whole.

In the structure of Figs. 5 and 6, the heating inductor is described as made up of two pairs of inductor coils 15a, 15b and 15c, 15d. Electrically the heating inductor 15 should be of such a design although physically it may comprise a group of separate coils or it may comprise a single continuous winding. The latter type of winding is represented in Figs. 7 and 8, which are top plan,

and front elevation, views, respectively, of a heating inductor 30 in which one pair of heating coils is electrically provided by the portions 30a, 30b wound and connected to develop magnetic fields in aiding phase and the other pair of coils is electrically provided by the portions 30c and 30d similarly wound to provide aiding magnetic fields. The pairs of sections 30a, 30b and 30c, 30d, however, are wound and connected to develop magnetic fields opposing each other. This relationship has been found most satisfactory in the apparatus of Figs. 5 and 6 for insuring substantially equal heating of the surface portions of the two arms 10a, 10b of the work piece 10.

While, in the apparatus described, the heating is substantially concentrated at the surface portion 10f, there is still very appreciable crowding of the field and consequent concentration of heat at the other sharp edge 10e, as shown in Fig. 4. In case it is desired to minimize the heating at this edge, the arrangement of the coils of the heating inductor may be modified. Two such alternative arrangements are illustrated schematically in Figs. 9 and 10. In Fig. 9 the coils 31 and 32 comprising the heating inductor are maintained parallel to each other but are laterally displaced, thereby warping the normal magnetic field to that illustrated. The insertion of the work piece 10 with the cross section of one arm 10b effectively cutting across the maximum intensity portion of the field, as shown, severely crowds the magnetic field only at the single sharply convex surface portion 10f so that the heating is concentrated only at this single surface region. Alternatively, in Fig. 10 the coils 33 and 34 of the heating inductor are arranged at an angle to each other while one arm 10b of the work piece 10 is inserted in the maximum intensity portion of the field between the coils so that only the single sharply convex surface portion 10f cuts across the field and crowds the field at such point, substantially concentrating the heating effect to the surface portion in this single region. It will be apparent that the heating inductor represented schematically in Figs. 9 and 10 can be embodied in heat treating apparatus of the type illustrated in Figs. 5 and 6.

While there have been described what are at present considered to be the preferred embodiments of the invention, it will be apparent to those skilled in the art that various changes and modifications may be made therein without departing from the spirit or scope of the invention.

What I claim as new is:

A high-frequency induction heating apparatus for heating a work piece including two substantially parallel arms, each arm thereof having a sharply convex surface portion, and for concentrating the heating over a predetermined portion of the convex surface of each arm of the work piece comprising, a heating inductor consisting of a continuous winding including two pairs of co-axial coils, the coils of each pair being spaced for the reception of an arm of said work piece and connected so that their magnetic fields are in aiding phase and the pairs of coils being closely adjacent and connected so that their fields are in opposing phase, for developing between the coils of each pair a high-frequency magnetic field which, in the absence of a work piece, has a relatively uniform field over its cross-sectional area, and positioning means for locating the work piece with each of its arms extending between the coils of one pair with said predetermined con-

vex surface portion thereof effectively cutting across said field.
